UNITED STATES PATENT OFFICE

105,168

DESIGN FOR A TEXTILE FABRIC

Curt Erwin Forstmann, Montclair, N. J.

Application October 9, 1935, Serial No. 58,911

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design pattern comprises elevated reticu-

lations on a background showing the weave, the reticulations being in groups, and irregular in outline incident to differences in tension of the flame threads by which they are delineated.

The background is puckered giving a rippled appearance to the surface of the fabric, and between parallel reticulations are sinuously disposed warp threads producing with the said parallel reticulations, ladder-like stripes.

I claim:

The ornamental design for a textile fabric, as shown and described.

CURT ERWIN FORSTMANN.
